A PACKAGING TRAY FOR FOOD PRODUCTS

William M. Miller, Jr., and Benton Neal Harris, Baltimore, Md., assignors to Gulf States Paper Corporation, Tuscaloosa, Ala., a corporation of Delaware

Filed Mar. 7, 1963, Ser. No. 73,877

Term of patent 14 years

(Cl. D58—12.6)

FIG. 1

FIG. 2

FIG. 3

FIGURE 1 is a top plan view of a packaging tray for food products, showing our new design;

FIGURE 2 is a side elevational thereof, the opposite side being the same in appearance; and

FIGURE 3 is a cross-sectional view on line 3—3 of FIGURE 1.

We claim:

The ornamental design for a packaging tray for food products, as shown and described.
